UNITED STATES PATENT OFFICE

159,287

SPORT SHIRT AND THE LIKE

Grace V. Neff, Chicago, Ill.

Application December 22, 1949, Serial No. 6,786

Term of patent 3½ years

(CL D3—25)

To all whom it may concern:

Be it known that I, Grace V. Neff, a citizen of the United States, residing at Chicago, in the county of Cook and State of Illinois, have invented a new, original, and ornamental Design for a Sport Shirt and the like, of which the following is a specification, reference being had to the accompanying drawing, forming part thereof.

In the drawing

Fig. 1 is a front elevational view of a sport shirt and the like, showing my new design, the sleeves being folded inwardly and a portion of the collar turned upwardly;

Fig. 2 is a rear elevational view thereof.

I claim:

The ornamental design for a sport shirt and the like, substantially as shown.

GRACE V. NEFF.
